Westinghouse Electric Corporation, East Pitts-
burgh, Pa., a corporation of Pennsylvania

Application February 16, 1945, Serial No. 578,156

7 Claims. (Cl. 200—52)

1

My invention relates to electric switching devices and, more comprehensively indicated, relates to switching devices of particular, though not exclusive, utility for controlling the starting equipment and propulsion equipment of electric torpedoes which otherwise have conventional shell, or housing, structures.

According to prior art practice, a trigger lever is pivotally mounted in the torpedo housing so that an end projects from the housing and upon firing of the torpedo engages a dog in the firing tube. This dog, when the torpedo rapidly moves through the tube, engages the trigger lever to actuate it from a non-operated position to an operated position. As it moves to the operated position, switch contacts are closed or opened, depending on the circuit arrangement of the starting gear, to control electric circuits that cause either directly or indirectly the operation of the electric torpedo propulsion equipment and other equipment on the torpedo.

It is apparent that such dog actuated switching devices are quite dangerous because the trigger lever may be actuated accidentally while handling the torpedo. While the arming devices are normally not operated by such actuation of the trigger lever, the propulsion equipment is started by such accidental actuation of the trigger lever with the consequent considerable danger to the personnel.

To obviate this considerable hazard, it has been proposed to provide inertia responsive starting switches operable upon firing of the torpedo from the firing tube. Such inertia responsive switches do eliminate the possibility of effecting the accidental starting by objects contacting or scraping the torpedo shell. The dangerous condition is, however, not that easily eliminated.

Torpedoes are often subjected to jars and impacts during handling. Gun fire of the ship carrying the torpedo and relatively minor shell hits made on the ship carrying the torpedo cause considerable accelerations of the torpedo with the result that the torpedo propulsion equipment is set in operation.

One object of my invention is the provision of switching means for obtaining the advantages of both a trigger switching means and inertia switching means with none of the disadvantages of either type.

A broad object of my invention is the provision for controlling electric circuits in response to both inertia and mechanical actuation.

Another somewhat more specific object is the provision of switching means operable only in response to the successive actuation of an extraneously applied mechanical force and an inertia force.

A more specific object of my invention is the provision of a pivoted trigger lever having an

unoperated position and an operated position and an inertia responsive switch interlocked with said trigger lever to prevent operation of the inertia responsive switch in response to inertia except when said trigger lever is in its operated position.

Other objects and advantages will become more apparent from a study of the following specification and the accompanying drawing, in which:

Figure 1 is a substantially vertical longitudinal sectional view of a switching device built in accordance with my invention; and

Fig. 2 is a substantially vertical transverse sectional view of the switching device, taken along line II—II, as shown in Fig. 1.

In Fig. 1, a fragment of the after-body 1 of a torpedo is shown to which a suitable supporting ring 2 is welded at 3. Mounted on the horizontal shoulder 4 is the outer upper generally circular flange 5 of the well 6.

The well 6 is generally rectangular in shape having the parallel side walls 7 and 8, the forward wall 10, and the aft end wall 9. The bottom of the well is provided with an opening 11. At the sides of the opening, the well 6 is provided with a pair of downwardly projecting bearing ears 12. These ears provide a seat or bearing for the relatively small arbor 13. This arbor 13 provides a bearing pivot for the vertically disposed lever 14. This lever 14 has a single rod-like, or bar-like lower end projecting a desirable distance below the bearing pivot, or arbor, 13 and above the arbor 13 and within the well is provided with a bifurcated, or U-shaped end. The upper ends of the legs of the U are provided with aligned trouser slots 15 open at the top.

A generally tubular bellows having an upper ring 16 hermetically secured to the bellows and a bottom closure 17 is disposed over the downwardly projecting end of lever 14. The upper ring 16 is braced, or soldered, or otherwise hermetically secured to the well so that the medium within the well enters the bellows but the bellows and well provide an effective barrier against flow of the medium within the well to the outside of the well and thus the inside of the torpedo.

To the closure 17, a resiliently mounted movable electric contact 18 is secured by any suitable means as shown. This movable contact 18 cooperates with a stationary contact 19 suitably secured, as shown, to the well 6.

Angular movement of the lever 14 thus causes these contacts to either close or open depending on the arrangement of the contacts and the direction of angular motion of lever 14. For the particular showing made in Fig. 1, clockwise rotation of lever 14 about the arbor 13 causes engagement between contacts 18 and 19.

Substantially directly above the opening 11, a pair of stub shafts 20 and 21 are positioned in the side walls 7 and 8, respectively. Side wall 8 is

provided with a hole entirely through the wall so that both stub shaft holes may be drilled and reamed from the outside. After drilling and reaming, the hole is sealed by a welded cap 21A. Stub shafts 20 and 21 are then assembled from the inside. In making this assembly, the following steps are taken:

- (1) Pin 21 assembled in its hole.
- (2) Pin 20 and snap ring 20A are assembled in the holes in pendulous member 22.
- (3) Pendulous member is inserted in cavity on pin 21.
- (4) Pin 20 is thrust into its hole.
- (5) Snap ring 20A is slid along pin 20 until it snaps into circular groove in pin 20, limiting lateral displacement of pendulous member and washer.

Pivotedly mounted on the stub shafts, as described above, is the inertia responsive, or pendulous member 22. This pendulous member is generally sector-shaped and formed into bifurcated upper ends 23 and 24 so that an over-center spring 26 may be disposed between the bifurcations. The upper ends of the bifurcations carry a bearing pin for a suitable roller 25.

The forward edges of the ends 23 and 24 are provided with bearing ears 27 for mounting the pin 28. At the upper region of the aft end wall 9, I provide an apertured projection 30 for receiving the upper aft end of tension spring 26, the lower forward end being secured to the pin 28. The disposition of pin 28 and projection is such that the direction of the spring force falls above the axis of the stub shafts 20 and 21 when the pendulous member is in the position shown.

The tension spring thus biases the pendulous member when in the position shown for clockwise rotation about the bearings.

From the foregoing disclosure, it is apparent that acceleration of the well 6 toward the left, in the absence of the mechanical elements herein-after discussed, will cause counterclockwise rotation of the pendulous member 22 and in so doing the pin 28 moves below the line determined by the projection 30 and the axis of the stub shafts 20 and 21 so that the pendulous member 22 will move with a snap action in a counterclockwise direction as soon as the spring 26 moves over-center.

The bifurcated ends 23 and 24 of the pendulous member 22 are provided with outwardly projecting crank pins 31 which rest in the aligned slots 15 in the ends of the U of the upper portion of lever 14. From this construction, it is apparent that over-center actuation of pendulous member 22 will effect snap action of contacts 18 and 19 through the operative interconnection between the pendulous member 22 and lever 14. Lower end of fork lever 14 is pivotally connected to U-shaped member 14A, which extends through and is welded water-tight to bottom closure 17. This pivot substantially reduces the force required to flex the bellows, by eliminating a reverse curvature of the bellows which would occur if the pivot were not provided.

To prevent accelerations of the well 6 toward the left or that general region, from rotating the pendulous member 22 except when such acceleration is caused by the firing of the torpedo from the firing tube, I provide latching means that lock the pendulous member in the non-operated position as long as the latching means are in the non-operated position.

The latching means comprise a removable base 32 snugly and firmly fitting in a specific position into the top or flange construction of the well 6.

This base 32 has a pair of depending bearing lugs 33 and 34 carrying the shaft 35. A trigger lever 36 is rigidly secured to the shaft 35 near the lug 34 and projects outwardly beyond the outer surface of the torpedo so that it may be actuated in a clockwise direction, as seen in Fig. 1, by a suitable dog in the firing tube for the torpedo.

The right-hand end, as seen in Fig. 2, of shaft 35 carries a cam arm 37 having an arcuate end 10 engaging the roller 25. The position of the cam arm 37 is such that as long as the trigger lever 36 is in its non-operated position—the position shown—the pendulous member 22 is locked against operation.

The aft region of the trigger lever 36 is provided with a cam surface 38 having concave depressions at 39 and 40 for coaction with the spring biased steel ball 41. This ball 41 holds the trigger lever 36 in the position shown until actuated by the dog in the firing tube at the time of firing of the torpedo. After the torpedo is fired from the tube, the ball 41 enters depression 39 to hold the trigger lever flush with the outside surface of the after body of the torpedo.

25 As an added precaution against accidental operation of the trigger lever, a locking pin 42 having the seal 43 may be disposed in a suitable opening in the trigger lever 36. When the torpedo is in position to be fired, the pin 42 is removed. The pin 42 may also be made of frangible material so that it shears off when the torpedo is fired.

To make certain that the pendulous member 35 remains in its operated position after firing, a latch strip 44 is pivoted at 45 and a soft spring, preferably having a limited expansion, biases the strip for counterclockwise rotation. When the pendulous member has moved to its extreme 40 counterclockwise position, the strip 44 engages the forward lower corner of member 22 thus latching it in position. Pin 29 is inserted in the forward face of the pendulous member, and limits the upward travel of latch 44.

45 When my special starting switching means are used for exercise runs, the pendulous member may be reset manually by removing the base 32 and, by a suitable rod depressing strip 44 while the pendulous member is positioned to its non-operated position. The base 32, with the trigger lever 36 in its non-operated position, is then restored to position.

50 While I have shown but one embodiment of my invention, it is apparent that others, after having had the benefit of my teachings, may devise apparatus for accomplishing the same or similar results. Therefore, I do not wish to be limited to the particular showing made, but wish to be limited only by the scope of the claims hereto appended.

55 I claim as my invention:

1. An electric switching device of particular utility with the starting equipment of a torpedo having a conventional shell, said switching device comprising in combination, a well adapted at its upper edges to be hermetically secured to the torpedo shell, a lever pivoted in the well and having one end, when said lever is in non-operated position, projecting beyond the surface of 65 the shell and the other end provided with a cam, a pendulous inertia member pivoted in the well and restrained against movement by said cam when said lever is in non-operated position regardless of acceleration of said well, and switch contacts operable by said pendulous inertia mem-

ber upon simultaneous operation of said lever and acceleration of said well.

2. An electric switching device of particular, though not exclusive, utility with the starting equipment and propulsion equipment of a torpedo having a conventional casing, said switching device comprising in combination, a mounting barrier having an opening therein and at its perimeter being hermetically rigidly secured to the torpedo housing, a flexible diaphragm closing the opening so that one side is exposed to the medium on the outside of the torpedo housing and the other side exposed to the medium on the inside of the torpedo housing, a stationary electric contact mounted on the barrier on the side exposed to the medium in the torpedo, a movable contact on the diaphragm, an inertia responsive element movably mounted on the barrier for moving the diaphragm to operate the movable contact, a lever pivoted on the barrier to be operable from the outside of the torpedo housing, said lever having an element which, when said lever is in one of its two operating positions, locks said inertia responsive element in non-operated position, whereby operation of both said lever and inertia responsive device is necessary to cause operation of said movable contacts.

3. An electric switching device of particular, though not exclusive, utility with the starting equipment and propulsion equipment of a torpedo having a conventional casing, said switching device comprising in combination, a mounting barrier mounted in the torpedo housing having a flexible diaphragm region, a movable contact on the diaphragm region, a stationary contact cooperatively mounted with reference to the movable contact, an inertia responsive member movably mounted on the barrier, a pivotally mounted latching lever adapted, when in one position, to lock said inertia responsive member against movement and when in a second position adapted to release said inertia member, whereby operation of both the lever and the inertia responsive member is necessary to effect operation of said movable contact.

4. An electric switching device of particular, though not exclusive, utility with the starting equipment and propulsion equipment of a torpedo having a conventional casing, said switching device comprising in combination, a well having flanges at its upper end for rigid hermetic attachment to the torpedo housing and having an opening at its lower end, a flexible generally tubular bellows at its upper end hermetically secured to the edges of the opening in the well, a closure for the lower end of the bellows, a pendulous inertia member pivoted in the well, a crank arm on the member, a tension spring at one of its ends secured to the well and at its other end so secured to the inertia member as to tend to rotate said pendulous member in a clockwise direction, a stop for limiting the rotation of the pendulous member in a clockwise direction so that the spring force is directed just to one side of the pivot of the pendulous member, said inertia member, when operated by acceleration of the well in a given direction, adapted to rotate counterclockwise to transfer the direction of the spring force to the other side of the pivot of the inertia member whereby said inertia member is biased to rotate in a counterclockwise direction by said spring, a trigger lever having a latching cam adapted to prevent operation of the inertia member except when said trigger lever has been actuated, a bel-

lows actuating lever pivoted intermediate its ends in the well having one end secured to the closure and the other end disposed to be actuated by the crank-arm of the inertia member.

5. An electric switching device of particular, though not exclusive, utility with the starting equipment and propulsion equipment of a torpedo having a conventional casing, said switching device comprising in combination, a well having outwardly directed flanges at its upper end for connection in the face of the torpedo housing, a trigger lever pivoted in the well and disposed to be actuated from a non-operated position to an operated position upon firing of the torpedo, a pivoted pendulous member mounted in the well, a spring mounted in the well for over-center actuation of said pendulous member, a cam on the trigger lever for holding said pendulous member in one over-center position when not in operated position, whereby operation of both said trigger lever and said pendulous member through acceleration of said well is necessary to effect movement of said pendulous member, and electric switch contacts operatively coupled to the pendulous member.

6. An electric switching device of particular, though not exclusive, utility with the starting equipment and propulsion equipment of a torpedo having a conventional casing, said switching device comprising in combination, a well having outwardly directed flanges at its upper end for connection in the face of the torpedo housing, a trigger lever pivoted in the well and disposed to be actuated from a non-operated position to an operated position upon firing of the torpedo, a pivoted pendulous member mounted in the well, a spring mounted in the well for over-center actuation of said pendulous member, a cam on the trigger lever for holding said pendulous member in one over-center position when not in operated position, whereby operation of both said trigger lever and said pendulous member through acceleration of said well is necessary to effect movement of said pendulous member, a diaphragm at the base of the well, closing said well, an operating member at one end secured to the diaphragm and at its other end operatively coupled to the pendulous member, and electric contacts disposed on the side opposite to the side of the diaphragm to which the operating member is secured to be operated by movements transmitted to the diaphragm upon actuation of the trigger lever and acceleration of the well.

7. An electric switching device of particular, though not exclusive, utility with the starting equipment and propulsion equipment of a torpedo having a conventional casing, said switching device comprising in combination, a well-shaped base mounted in the housing having a flexible diaphragm closing its bottom, a stationary electric contact mounted on the outside of the base adjacent the diaphragm, a movable contact mounted on the diaphragm adapted to cooperate with said stationary contact, a pendulous member, a spring for over-center operation of said pendulous member upon angular movement of the pendulous member by acceleration of the base, and a trigger lever having a non-operated position before firing of the torpedo and an operated position after firing of the torpedo, said trigger lever having an element for preventing angular motion of the pendulous member except when said trigger lever is in its operated position.

WILLIAM B. ELMER.
